UNITED STATES PATENT OFFICE.

JOHN S. PEOPLES, OF WASHINGTON, DISTRICT OF COLUMBIA.

AMMUNITION-PACKING CASE.

1,306,312.

Specification of Letters Patent. Patented June 10, 1919.

Application filed November 29, 1918. Serial No. 264,690.

(FILED UNDER THE ACT OF MARCH 3, 1883, 22 STAT. L., 625.)

To all whom it may concern:

Be it known that I, JOHN S. PEOPLES, a citizen of the United States, stationed at Washington, District of Columbia, have invented an Improvement in Ammunition-Packing Cases, of which the following is a specification.

The invention described herein may be used by the Government, or any of its officers or employees in prosecution of work for the Government, or by any other person in the United States, without payment of any royalty thereon.

This invention relates to improvements in ammunition packing cases, and refers more particularly to machine gun ammunition containers of the "layer feed" type.

The principal object of the invention is to provide a simple and effective container for loaded machine gun belts in which provision is made for the ready application of the filled container to the tripod of a machine gun, from which the ammunition therein may be fed directly to the machine gun, without the necessity of transferring the loaded belt into a permanent ammunition box carried by the gun.

Another important object of the invention is the provision of means whereby the ammunition container may be sealed to protect the contents from the weather, and which sealing operation will be effected in such a manner as not to interfere with the speedy access to the contents of the container.

With the foregoing objects in view, the invention comprises the new and useful details of construction, arrangement and combination of parts, which will be fully described herein, illustrated in the accompanying drawings, and pointed out more specifically by and in the appended claims.

In the accompanying drawings, wherein the preferred embodiment of the invention is shown, like reference characters refer to like or corresponding parts throughout the several views.

In the drawings:

Figure 1 is a side elevation of an ammunition container constructed in accordance with my invention, portions thereof being broken away to better illustrate the underlying parts.

Fig. 2 is an end elevation of the sealed container. 55

Fig. 3 is an elevation of the opposite end of the container.

Fig. 4 is a top plan view of the container of my invention, a portion of the cover element being unsealed and turned back in a position from which the ammunition belt may be fed to the machine gun.

Fig. 5 is a sectional view of my container, the view being taken on line 5—5 of Fig. 1.

Fig. 6 is a fragmentary sectional view of my container taken on line 6—6 of Fig. 2.

Referring now to the drawings in general, my container as illustrated comprises a pair of spaced apart side plates 10, preferably formed of wood or fiber board and provided with sheet metal side covers 11 on the outer faces thereof, which side covers are bent inwardly over the upper and lower edges of the side plates as is illustrated clearly in Fig. 5. The upper in-turned edges are designated as 12 and are rolled to form beads extending longitudinally of the container and projecting above the container in position to protect the top thereof. A vertical flange 12' is formed on the inner edge of the roll 12, the flanges 12' preferably extending inward to the inner edge of the side plates 10. The lower in-turned edges are designated as 13, the same being turned upward at 14 about the inner faces of side plates, where engagement is made with a metallic bottom 15. Front and rear end pieces 16 and 17, respectively, also formed of sheet metal, are soldered or otherwise engaged at each end of the device about the end edges of the aforesaid side covers 11. The end pieces are recessed between the side plates, as at 18, and may be ribbed as at 19 to give rigidity to the assembled container. The upper edge of the front end piece is turned inwardly at 23 and rolled downwardly as at 24 against the inner face of the end, for a purpose which will be hereinafter pointed out. The upper edge of the rear end sheet is turned inwardly at right angles to form an over-lapping lip 21 and soldered to the upper face of the in-turned edges 12' of the side covers.

Upon the projecting lip 21 and extended longitudinally of the container between the longitudinal beads 12, I provide a cover 22,

preferably formed of pliable sheet metal, the cover being engaged by soft solder to the aforesaid lip, to the underlying edges 12' of the side covers and to the uppermost 5 portion of the in-turned edge 23 of the front end sheet. The forward end of the cover strip is turned down at 25 and engaged to the front end 16 by soft solder, a handle 26 being engaged to the end thereof in any 10 suitable manner.

As an auxiliary means of holding the cover 22 in place, especially effective when the filled container is being transported, I have provided a metallic clip 27 which is 15 fixed to the front end piece 16 and which is adapted to be bent over the handle to removably hold the same firmly in place against the end of the container.

The rear end of the container is provided 20 with a fabric or leather handle 28, a pair of brackets 29 being fixed to the rear end piece 17 in spaced apart relation to receive the looped ends of the handle, as is illustrated in Fig. 3. When handle 28 is in use the container is suspended, the front end becoming the bottom of the container in an obvious 25 manner.

The normal position of the container when in use on a machine gun is as shown in Fig. 30 1, the container being engaged in the ammunition case bracket on the machine gun tripod not shown. To this end, the container is provided with vertical grooves 30 on each side adjacent to the front edge of the side 35 units, adapting the container to fit between the usual vertical flanges of the tripod brackets not shown. The lower front end corners of the container are tapered as at 31 to provide necessary clearance with respect to the 40 tripod.

As an essential part of my container, I provide a plurality of spacing strips 32 carried within the container, but not engaged thereto. Strips 32 are formed of sheet metal 45 and are engaged together by being perforated at 32' and strung on a rod or wire 33 adapted to be positioned longitudinally of the container and provided with enlarged heads 34 on each end. Said strips are adapted to be forced vertically between one of the side plates 10 and the belt 35 on which the cartridges 36 within the container are carried. The strips are spaced between the projecting nosed ends of the cartridges to prevent the belt from slipping off the tapered 50 cartridges during handling of the filled container. The spacing strips are formed of pliable metal, as is the rod 33 upon which they are mounted, allowing the spacing strips 55 and rods to be readily withdrawn from the container, even when the cover 22 is withdrawn only a portion of the distance across the top, as is shown in Fig. 4.

In bringing the container into use on a 60 machine gun, the operator will disengage

handle 26 by bending the clip 27 out of engagement therewith and, by grasping the handle 26 and pulling the cover upwardly and rearwardly, break the soldered joint between the container and cover. 70

It is preferable that only a portion of the cover be torn off, as the contents will be accessible when the forward half of the cover is rolled back. Should only a portion of the ammunition be used the cover will still be 75 engaged adjacent to the rear end thereof, and it may be replaced by drawing the free end of the cover forward to the sealed position where the handle 26 may be again engaged by the clip. 80

When the container is opened, the spacing strips may be readily removed, and the container inserted in the receiving bracket on the machine gun tripod, whereupon the loaded belt may be fed to the gun in the well known manner, the belt being allowed to pass over the rolled edge 24 of the end 16, the rolled portion providing an unobstructed guide-way for the fed belt. 85

Having described the invention, what is 90 claimed as new is:

1. The combination of a container adapted to receive a cartridge-belt, said container including side plates formed for detachable engagement with a suitable support, a removable cover for closing the container, and means carried by the container and adapted for detachable engagement with the cover to retain the cover in closed position. 95

2. The combination of a container adapted to receive a cartridge-belt, said container including side plates formed for detachable engagement with a suitable support, and a removable cover for closing the container. 100

3. The combination of a container adapted to hold a cartridge-belt, a cover for closing the container adapted to be rolled back to open the container, a handle attached to the cover whereby the cover may be rolled back, and means carried by the container and adapted for detachable engagement with the handle to hold the cover in normally closed position. 105

4. The combination of a container adapted to hold a cartridge-belt, a flexible cover for closing the container adhesively secured to the container and a handle attached to the cover whereby the cover may be turned back to break the adhesive connection and open the container. 115

5. The combination of a container adapted to hold a cartridge-belt, a cover for the container adhesively secured along its longitudinal edges to the container, a handle attached to the cover for drawing the cover to progressively detach the cover from the container, and pliable spacers within the container and adapted for removal from the container when the cover is partially withdrawn. 125

6. The combination of a container adapted to hold a cartridge-belt, a removable cover for closing the container and spacers within the container adapted for removal upon 5 partial opening of the cover.

7. The combination of a container adapted to hold a cartridge-belt and including end plates, the upper edge of the front end plate turned inwardly and downwardly to 10 provide a roll over which a cartridge belt may be guided and a detachable cover for the container.

8. An ammunition packing case, consisting of a container adapted to receive cartridges and a cover carried by said container and adapted to be rolled back to provide an 15 exit passage for said cartridges.

9. An ammunition packing case, consist-

ing of a container, a cover carried by said container and adapted to be operated to provide access to said container, a handle mounted in said cover for opening and closing the cover, and means for engaging the handle to retain the handle with cover in closed position. 20

10. An ammunition packing case, consisting of a container adapted to receive a belt containing cartridges, a cover for closing said case provided with means for raising the cover to permit access to the belt of 30 cartridges, fastening means to secure the cover in closed relation to the container, and a carrying handle secured to said container. 25

JOHN S. PEOPLES.
